(57) **CLAIM**

The ornamental design for a “blueprint strap wrap,” as shown and described.

DESCRIPTION

FIG. 1 is a perspective view of a blueprint strap wrap in an open configuration, showing my new design;

FIG. 2 is a perspective view thereof, illustrating the blueprint strap wrap in a rolled configuration;

FIG. 3 is a top plan view thereof;

FIG. 4 is a bottom plan view thereof;

FIG. 5 is a left side elevational view thereof, the right side elevational view being a mirror image thereof;

FIG. 6 is a front elevational view thereof; and,

FIG. 7 is a rear elevational view thereof.

The broken line showing of a pencil and a roll of blueprints is for illustrative purposes only and forms no part of the claimed design.
